United States Patent Office

Des. 194,049
Patented Nov. 13, 1962

194,049

GARDEN TOOL

Katsumi Harano, 5609 Bowcraft, Los Angeles, Calif.

Filed Oct. 16, 1961, Ser. No. 67,080

Term of patent 14 years

(Cl. D35—2)

Fig. 1.

Fig. 2.

Fig. 3.

Fig. 5.

Fig. 6.

FIG. 1 is a perspective view of a garden tool showing my new design;

FIG. 2 is a side elevation thereof, the opposite side being a mirror image of the side shown;

FIG. 3 is a top plan view thereof;

FIG. 4 is a bottom plan view thereof;

FIG. 5 is a front elevation thereof; and,

FIGURE 6 is a rear elevation thereof.

I claim:

The ornamental design for a garden tool, substantially as shown and described.
